[57] CLAIM

The ornamental design for a storage cabinet, as shown and described.

DESCRIPTION

FIG. 1 is a top perspective view of the storage cabinet showing my new design;

FIG. 2 is a left side elevational view, the right side being a mirror image thereof;

FIG. 3 is a top plan view thereof;

FIG. 4 is a front elevational view thereof;

FIG. 5 is a rear elevational view thereof;

FIG. 6 is a top perspective view, with the drawer in a closed position; and

FIG. 7 is a top perspective view of another embodiment of my storage cabinet shown in FIG. 4.

The broken line showing of file trays in FIG. 1 is for illustrative purposes only and forms no part of the claimed design.
